(57) CLAIM

The ornamental design for a packaging for foodstuffs, as shown and described.

DESCRIPTION

The patent or application file contains at least one drawing executed in color. Copies of this patent or patent application publication with color drawing(s) will be provided by the Office upon request and payment of the necessary fee.

1. Packaging for foodstuffs

1.1 : Perspective

1.2 : Unfolded

There is a transparent window on the front to show the product, symmetrical lines outwards on the top, two human pasta carrying figures on the front, and motifs on the side of the package.
